UNITED STATES PATENT OFFICE.

FRANKLIN PIERCE HUMMEL, OF BELLEVUE, OHIO.

STEAM-ENGINE.

SPECIFICATION forming part of Letters Patent No. 757,750, dated April 19, 1904.

Application filed July 16, 1903. Serial No. 165,795. (No model.)

To all whom it may concern:

Be it known that I, FRANKLIN PIERCE HUMMEL, a citizen of the United States, residing at Bellevue, in the county of Huron and State of Ohio, have invented a new and useful Steam-Engine, of which the following is a specification.

This invention relates to certain improvements in steam and other engines operable by a fluid under pressure, and has for its principal object to provide a novel form of engine in which the pressure and the expansive force of steam may be utilized to better advantage than in engines of ordinary construction.

A further object of the invention is to provide an engine in which both the cylinder and piston, or the cylinders and pistons of a duplex or compound engine, will be traveled in the same direction, but at different speeds, in order to allow the same quantity of steam to act more effectively than it would in the case of a movable piston and stationary cylinder, such as are employed in engines of the ordinary type.

A still further object of the invention is to provide a novel form of valve-operating mechanism adapted especially for use in connection with engines having movable cylinders and arranged and constructed in such manner as to compensate for the movement of the cylinder and permit proper manipulation of the valve to govern the flow of steam to and from the cylinder.

With these and other objects in view, as will more fully hereinafter appear, the invention consists in the novel construction and arrangement of parts herein described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a longitudinal sectional elevation of an engine constructed in accordance with the invention.

Fig. 2 is a plan view of the same, partly in section, the parts being shown in the position assumed at half the outstroke. Fig. 3 is a side elevation of a portion of the mechanism with the parts in a different position from that shown in Fig. 1. Fig. 4 is a longitudinal sectional elevation of the engine on the line 4-4 of Fig. 2.

Similar numerals of reference are employed to indicate corresponding parts throughout the several figures of the drawings.

In carrying out the invention I employ a pair of cylinders 1 and 2, containing, respectively, pistons 3 and 4, together with a main crank-shaft 5, to which both the cylinders and the pistons are connected, the several parts being mounted on a suitable supporting-frame 6, having bearings for the crank-shaft and cross-head guides and similar supports for the cylinders and the piston connections. The pistons 3 and 4 are connected, respectively, by rods 7 and 8 to cross-heads 9 and 10, adapted to suitable guideways 11 of the frame. The cross-head 9 is connected by a rod 12 to a crank 13 on the main shaft, and the cross-head 10 is in similar manner connected to a crank 15 on said shaft. The two cranks are arranged at an angle to each other in order to prevent the engine stopping on a dead-center, and an angular distance between the two is preferably as slight as will permit one or other, or both, of the pistons operating effectively to turn the crank-shaft past a center.

The frame of the engine is provided with guides 16 for the reception of blocks or cross-heads 17, carrying the two cylinders 1 and 2, and said cylinders are connected together by a single steam-chest 18, containing ordinary D-valves and provided with steam and exhaust connections. On the main shaft are two eccentrics 20, the straps 21 of which are connected by rods 22 to pins or studs 23, projecting from the sides of the cylinders, the eccentrics and the cranks being so arranged as to permit movement of both the pistons and the cylinders in the same direction, but at different speeds, it being noted that the

length of the cylinders is less than the stroke of the pistons, so that it is only necessary to move the cylinders for a distance equal to the distance between the length of such cylinder 5 and the length of the stroke.

At the rear end of the steam-chest are two stuffing-boxes 24 and 25, through which respectively pass a steam-inlet pipe 26 and an exhaust-pipe 27, the pipes being stationary 10 and supported in part by the frame, while the stuffing-boxes permit of the passage of steam to and from the chest with but little danger of leaking. The opposite sides of the steam-chest are provided with the usual ports 28 and 15 29, the ports 28 leading to the opposite ends of the cylinders and the ports 29 communicating with the exhaust-pipe 27. In the steam-chest are D-valves 30 and 31, adapted, respectively, to govern the flow of steam to 20 and from the cylinders 1 and 2, and these valves are connected, respectively, by rods 33 and 34 to eccentric-straps 35 and 36, surrounding eccentrics 37 and 38 on a crank portion 39 of the main shaft 5. The crank 39 is 25 considerably shorter than the main cranks 13 and 15 and is disposed in an angular plane between the two cranks 13 and 15, so as to properly move the valves in accordance with the speed of movement of the cylinder, while 30 the eccentrics 37 and 38 are arranged in different angular positions, corresponding to the different angular positions of the main cranks 13 and 15.

The operation of the engine, the parts being 35 in the position shown in Fig. 1 and the main crank-shaft revolving in the direction indicated by the arrow, the cylinder and cylinder-actuating eccentrics are at the limit of outstroke, while the crank 15 has completed 40 the outstroke and is started on the return or instroke. As this time the crank 13 has not yet completed the outstroke, but will do so before the eccentrics have moved the cylinders on the instroke to any material extent, 45 there being sufficient space left in the end of the cylinder to permit the piston 3 to complete its movement. At this time the valve 30 will be in the act of closing and the valve 31 will be about to open. The positions of 50 adjustment of the two eccentrics 37 and 38 will then determine the operative movement of the valves, and the latter may be held open during the whole or a portion of the instroke of the pistons and moved to exhaust from the 55 outer ends of the cylinders and to admit steam to the inner ends of said cylinders at the completion of the instroke.

It will be observed that the relation of parts is such that the pistons will be traveled at a 60 much greater rate of speed than the cylinders, so that the steam will not be allowed to expand to such an extent as it would with a

stationary cylinder, owing to the fact that the cylinder follows up the movement of the piston, while the superior force exercised by the 65 cranks on the shaft over that which the cylinders under the influence of the same pressure can exercise on the shafts through their eccentrics will insure proper movement of the engine, especially if a balancing wheel or 70 wheels be employed to keep up the momentum of the main shaft.

Having thus described the invention, what is claimed is—

1. In a steam-engine, a base-plate, a pair 75 of parallel cylinders guided on the base-plate, a steam-chest disposed between the two cylinders and having suitable steam inlet and escape pipes, a pair of valves arranged in the steam-chest for governing the flow of steam 80 therethrough to the cylinders, a main shaft, pistons arranged in the cylinders, angularly-disposed cranks connected one to each of the pistons, eccentrics carried by the main shaft and operatively connected to the cylinders to 85 impart movement to the cylinders in the same direction as the pistons, and means operable by the shaft for moving the valves.

2. In a steam-engine, a bed-plate, a pair of parallel cylinders guided thereon, a steam-chest disposed between the two cylinders, a pair of valves arranged in the steam-chest for governing the flow of steam therethrough to the cylinders, pistons in said cylinders arranged to travel one slightly in advance of 90 the other, a crank-shaft, angularly-disposed cranks carried by the shaft and connected one to each of the pistons, eccentrics mounted on the shafts and connected to the cylinders, auxiliary cranks carried by the shafts and having 100 crank-pins, and valve-operating eccentrics mounted on said crank-pins, substantially as specified.

3. In a steam-engine, a pair of connected 105 cylinders, a single valve-chest for said cylinders, valves arranged in the chest, steam supply and exhaust pipes connected to the chest, a main shaft, cranks arranged at an angle to each other and connected to the respective pistons, eccentrics carried by the shaft and 110 connected to the cylinders, a crank on the shaft, and eccentrics carried by the crank and connected to the respective valves.

4. In a steam-engine, a frame having guide-ways, a pair of movable cylinders adapted to 115 said guideways, a single steam-chest connecting the cylinders, steam supply and exhaust pipes extending through stuffing-boxes to the steam-chest, valves disposed in the chest for governing the flow of steam to and from the 120 respective cylinders, a main crank-shaft having bearings on the frame, cranks disposed at an angle to each other and connected to the respective pistons, eccentrics mounted on said

shaft and connected to the cylinders, a crank carried by the shaft, and a pair of eccentrics carried by the crank and disposed at an angle to each other corresponding to the angular relation of the piston-cranks, said eccentrics being connected to the respective valves, substantially as specified.

In testimony that I claim the foregoing as my own I have hereto affixed my signature in the presence of two witnesses.

FRANKLIN PIERCE HUMMEL.
